[21] Appl. No.: **44,476**

[57] CLAIM

[22] Filed: **Sep. 25, 1995**

The ornamental design for a frame tracer and centering device in particular for ophthalmic lenses, as shown and described.

[30] Foreign Application Priority Data

Mar. 23, 1995 [FR] France 951 739

DESCRIPTION

[51] LOC (6) Cl. **16-06**

FIG. 1 is a front view showing my new design;

[52] U.S. Cl. **D16/130**

FIG. 2 is a right side view thereof;

[58] Field of Search D16/130, 221-222,

FIG. 3 is a left side thereof;

D16/225, 227; D24/174, 150, 172; 356/124-127,

FIG. 4 is a top plan view thereof;

391-393

FIG. 5 is a back view thereof; and,

[56] References Cited

FIG. 6 is a bottom plan view thereof.
